Primary Examiner — Richard E Chilcot(74) *Attorney, Agent, or Firm* — Birch, Stewart, Kolasch & Birch, LLP(57) **CLAIM**

The ornamental design for a pulsator for washing machine, as shown and described.

DESCRIPTION

1. Pulsator for washing machine
- 1.1 is a perspective view of a pulsator for washing machine, showing our new design;
- 1.2 is a front elevation view thereof;
- 1.3 is a rear elevation view thereof;
- 1.4 is a left-side elevation view thereof;
- 1.5 is a right-side elevation view thereof;
- 1.6 is a top plan view thereof; and
- 1.7 is a bottom plan view thereof.
